UNITED STATES PATENT OFFICE.

KARL HUGH SIEVER, OF KEYSER, WEST VIRGINIA.

PADDED COVERING FOR IRONING ROLLS.

Application filed November 1, 1924. Serial No. 747,244.

To all whom it may concern:

Be it known that I, KARL H. SIEVER, a citizen of the United States, and a resident of Keyser, in the county of Mineral and State of West Virginia, have invented certain new and useful Improvements in Padded Coverings for Ironing Rolls, of which the following is a specification.

My present invention relates to laundry apparatus and more particularly to the padded rolls of ironing machines of various types, my invention especially having to do with the coverings of such rolls whose purpose is to form a yielding ironing surface in conjunction with a steam heated surface against which the roll rotates. This steam heated surface may be the surface of a cylinder or concave depending upon the type of ironing machine in which the roll is used.

At present the padded rolls of ironing machines are used both with and without surface layers of asbestos, a wide strip of padding being wound upon the roll with its inner and outer edges approximately in line. A covering strip or ironing cloth of muslin, duck or other suitable material is then similarly wound around the padding, and the winding of both the padding and the covering cloth is of course accomplished in a direction opposite that of rotation of the roll in use. The result is that when the roll is in use tightly against the highly heated surface with which it cooperates, the covering cloth and padding are gradually drawn tighter and tighter around the roll by the friction. This tightening of the covering, coupled with the intense heat to which it is subjected, causes the covering including the pad and cloth to quickly pack hard and unyielding and to soon char so that its useful life is over. It is then necessary to recover the roll, which is both tiresome and time killing in addition to being a costly operation in view of the present high price of the padding and covering cloth.

The primary object of my present invention is to provide a means of padding and covering ironing rolls in such manner that the covering will not pack or char and will

for this reason outlast the usual covering many times.

In the accompanying drawing which illustrates my present invention and forms a part of this specification,

Figure 1 is a sectional view through a series of ironing rolls showing the practical application of my invention,

Figure 2 is a detail perspective view of one end portion of the covering proposed by my invention, and

Figure 3 is an enlarged sectional view through a cylinder and my improved covering applied thereto.

Referring now to these figures and particularly to Figure 1, I have shown a series of ironing rolls 10, disposed in engagement with steam chests or steam heated concaves 11 although it is to be understood that the covering as proposed by my invention for these rolls 10 is to be used on ironing rolls irrespective of the relative arrangement of the rolls or the type of steam heated surface with which they are in contact.

My invention proposes a covering as shown particularly in Figures 2 and 3, consisting of a series of strips 12 of woven padding, applied to a carrier in the form of a single piece of cloth 13, the latter preferably of muslin, duck or similar material. To this carrier the strips of padding are secured as by stitches 14, along the rear edges of the strips, the latter being of uniform width and in successive uniform overlapping relation and spaced apart a distance 85 equal to one-half of the widths of the strips thus bringing the free edge of each strip in overlapping relation to the center of the next strip and approximately in line with the connected edge of the third strip 90 and so on throughout the series, the length of the series as a whole conforming of course to the circumference of the roll 10 to which it is applied.

Thus by winding the carrier cloth 13 around the cylinder with the free edges of the strips 12 turned in a direction opposite to the direction of rotation of the roll, it is obvious that in the rotation of the roll the several strips of padding are free to squeeze

into the space between the roll and the steam heated surface with which it cooperates, and yet each strip having once passed by such steam heated surface is free to instantly 5 yield away from the roll and to not only expand but to allow air to circulate around and beneath the same. This obviously permits the strips of padding arranged as proposed by my invention to retain their natural resiliency and to avoid packing and charring.

The covering cloth is in accordance with my invention likewise composed of a series of strips 15, of somewhat greater width than 15 the strips of padding 12, each of the covering strips overlying one of the strips of padding and secured at its rear edge to its respective padding strip and to the carrying cloth 13, preferably by the same 20 stitches 14 used to secure the anchored edges of the padding strips. The covering strips 15 thus overlap one another in a manner similar to the strips of padding and leave the latter free to yield and expand as 25 previously described. Moreover they together form a covering or ironing cloth, and in view of the augmented length of life of the padding and the probability that a renewal of the covering or ironing cloth 30 will be desirable during the continuance of such life of the padding, two covering strips may be secured in superimposed relation upon each strip of padding so that when a renewal of the covering or ironing cloth is 35 desired, the outermost strips may be removed, that is cut off adjacent to the lines of stitching 14 so that the innermost strips will thus be left to form a clean, new covering or ironing surface.

40 I claim:

1. A covering for ironing rolls consisting of a carrier cloth in a single piece adapted to be wound around such rolls, a series of strips of padding in uniformly overlapping 15 relation on the carrier cloth, each strip being secured at its innermost edge to the cloth and being otherwise free, the said strips being spaced apart a distance equal to one-half of the widths of the strips, and a series 20 of covering strips overlying the several strips of padding, the said covering strips being of greater width than the strips of padding and secured at one edge to the con-

nected edges of the strips of padding whereby to form an external ironing cloth in their 55 freely overlapping relation.

2. A covering for ironing rolls including a series of circumferentially overlapping pads, each pad being anchored at its innermost edge and being otherwise free to yield away from the roll, the pads being spaced apart a distance equal to one-half of the widths thereof, and means carried by and yieldable with the pads for forming a covering or ironing cloth therearound.

3. A covering for ironing rolls including a series of circumferentially overlapping pads, each pad being anchored at its innermost edge and being otherwise free to yield away from the roll, the pads being spaced apart a distance equal to one-half of the widths thereof, and cloth covering strips of greater widths than the pads, secured to overlie the several pads and in similar freely overlapping relation whereby to form a 75 covering or ironing cloth around the pads and permit the latter to freely yield in operation.

4. In a covering for ironing rolls, a series of circumferentially overlapping pads of similar size, and a flexible carrier to which each pad is secured along one edge, said pads being disposed in uniformly spaced relation and having their remaining portions free for yielding movement relative to 85 one another.

5. In a covering for ironing rolls, a series of independent pads in circumferentially and uniformly overlapping relation, and means carried thereby forming a covering 90 cloth therefor without impairing the independent yielding qualities of the pads in use.

6. In a covering for ironing rolls, a series of circumferentially overlapping pads arranged to form a padded surface of uniform 95 thickness around the roll and each anchored at one edge, said pads having their remaining portions free and yieldable with respect to the roll and to one another.

7. A covering for ironing rolls consisting of series of pads and cover strips arranged in circumferentially overlapping relation and having their overlapping portions freely and independently yieldable toward and away from one another.

KARL HUGH SIEVER.
